(57) **CLAIM**

I claim the ornamental design for a shoe, substantially as shown and described.

DESCRIPTION

FIG. 1 is a left side view of a shoe showing my new design. FIG. 2 is a right side view of the shoe shown in FIG. 1; FIG. 3 is a top plan view of the shoe shown in FIGS. 1-2; FIG. 4 is a frontal view of the shoe shown in FIGS. 1-3; and, FIG. 5 is a rear view of the shoe shown in FIGS. 1-4. The surfaces of the shoe that are not shown in the drawings, or described in the specification, form no part of the claimed design.
